UNITED STATES PATENT OFFICE.

MICHAEL J. TRACY, OF ST. LOUIS, MISSOURI.

LATCH.

Application filed April 23, 1928. Serial No. 271,992.

This invention relates to improvements in latches.

An object of the present invention is to provide an improved latch for use in latching doors or gates, and comprising one or more concealed longitudinally movable locking bolts mounted in the wall instead of on the door or gate and designed and adapted for vertical movements to engage the ends of the door or gate in concealed and inaccessible positions.

Another object of the invention is to provide an improved latch possessing the advantages and merits of the latch herein disclosed, reference being made to the accompanying drawing in which—

Fig. 1 is a view showing the latching bolts in engagement with the upper and lower extremities of the gate or door.

Fig. 2 is a vertical sectional view of the upper portion of the door and wall showing the engagement of the latch bolt with the upper portion of the door in an inaccessible location.

Fig. 3 is a cross sectional view showing the latch bolt in engagement with the lower portion of the gate or door in an inaccessible position.

In the specific embodiment of the invention shown the upper latching bolt 1 is enclosed within a stationary metallic enclosure 2, the upper end of said latching bolt projecting through the upper end of said enclosure 2.

The lower latching bolt 3 is also enclosed within a metallic enclosure 4 and projects downwardly through the lower end of said enclosure 4.

As shown, the door 5 is mounted for sliding movements along the wall of which the enclosures 2 and 4 form a part. This door 5 is operatively supported by a bracket 6 projecting from its upper end and seating upon balls 7 mounted upon a support 8. The bracket 6 is provided with a lateral extension 9 having a longitudinal slot 9^a formed with notches in its opposite edges in which the upper end of the locking bolt 1 engages when the door 5 is closed. The lower end of the door 5 supports a strong bar 10 which extends for longitudinal movements under the lower end of the enclosure 4 and has a notch 11 adapted to receive the lower end of the lower latching bolt 3 when the door 5 is closed.

The supporting bracket 6 for the door is located within an enclosure comprising a vertical wall 12, end walls 13 of which one

is shown, said end walls being provided with inturned flanges 14, and an additional wall 15 fitted upon the flanges 14 and having its edge engaging under a holder 16. A bar 17 ⁶⁰ engages with brackets 18 on the wall 15 and thus prevents detachment of said wall until said bar 7 is removed. The upper enclosure thus constructed confines and renders inaccessible the door supporting structure and the ⁶⁵ latching device for the upper end of the door so that it is impossible to tamper with the latching devices.

Near its upper end the upper latching bolt 1 is provided with notches 19 which receive ⁷⁰ the edges of the bracket extension 9 at the sides of the slot 9^a when the latching bolt 1 is in its upper or unlocking position. When the lower latching bolt 3 is in its upper or unlocking position the lower end thereof is ⁷⁵ out of the notch 11. Thus when both latching bolts 1 and 3 are in their unlatched positions the door 5 is capable of lateral movement from closed position; and, when the door 5 is in any of its intermediate positions, ⁸⁰ that is to say when said door is not entirely closed, the lower end of the lower latching bolt 3 is above the bar 10 and cannot be moved downwardly, and the upper walls of the notches 19 of the upper latching bar 1 are ⁸⁵ above the bracket extension 9 and cannot be moved downwardly.

The lower end of the latching bolt 1 is connected with an actuator 20, and the upper end of the latching bolt 3 is connected with an ⁹⁰ actuator 21. The specific construction of these actuators and their engagement with the respective latching bolts 1 and 3 are not shown because the same do not constitute a part of the present invention, it being sufficient for present purposes to know that turning movement of the actuator 20 will raise the latching part 1 from latched to unlatched position, and vice versa; and turning movement of the actuator 21 will move the latch bolt 3 from latched to unlatched position, and vice versa.

The provision of actuators of suitable construction is well within the skill of those skilled in this art and, since the specific features of these actuators are not herein claimed, further illustration or description thereof is deemed unessential. For, the essence of the present invention exists in that construction, combination and arrangement ¹⁰⁵ of parts wherein the latch bolts are wholly concealed and are inaccessible so that it is im-

possible to know by mere observation whether the door is latched or unlatched, and it is also impossible to tamper with the latch bolts or to know from observation the manner in which the latch bolts engage the parts to be latched.

I am aware that the construction and arrangement of the devices forming the invention may be varied within equivalent limits without departure from the nature and principle thereof. I do not restrict myself unessentially in these or other respects, but what I claim and desire to secure by Letters Patent is:—

- 15 1. The combination with a wall, a door, and devices for supporting said door for sliding movements along said wall, of a bar mounted in said wall for vertical sliding movements to and from latching engagement with said devices, and means enclosing and preventing access to said devices.
- 20 2. The combination with a wall, a door, and devices for supporting said door for sliding movements along said wall, of a bar mounted in said wall for vertical sliding movements to and from latching engagement with said devices, and means enclosing and preventing access to said devices and said bar.
- 25 3. The combination with a wall, a door, and means for supporting the door for sliding movements along the wall, of latch bars movable to and from latching engagement

with the upper and lower portions of the door, and means enclosing and preventing access to said supporting devices and said bars.

4. The combination with a wall, a door, a supporting element in connection with the wall, and a bracket attached to the door for operation on said supporting element, of an enclosure enclosing and preventing access to said bracket, and a latch bar operating in said enclosure to and from locking engagement with said bracket.

5. The combination with a wall and a door slidable along said wall, of an enclosure above said door, a part extending from said door into said enclosure, and a latch bar mounted in the wall for engaging said part of said door in said enclosure.

6. The combination with a wall, an enclosure in said wall, and a door movable edge-wise along said wall and having a part extending under said enclosure, of a latch bar mounted in said enclosure and movable to and from engagement with said part of said door.

7. The combination with a wall, rigidly stationary enclosing means in connection with said wall, latch bars confined within said enclosing means, and a door movable laterally along said wall to and from position to be engaged by said latch bars.

MICHAEL J. TRACY.
